CLAIM

The ornamental design for a dehumidifying, sterilizing and deodorizing machine for garments, as shown and described.

DESCRIPTION

1. Dehumidifying, sterilizing and deodorizing machine for garments
  - 1.1 : Perspective
  - 1.2 : Front
  - 1.3 : Back
  - 1.4 : Left
  - 1.5 : Right
  - 1.6 : Top
  - 1.7 : Bottom

(Continued)

The gist of the present ornamental design is a combination of shape and pattern of “Dehumidifying, sterilizing and deodorizing machine for garments” as shown and described.
